UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed December 22, 1922. Serial No. 608,392.

This invention relates to improvements in anti-friction bearings.

One object of the invention is to provide an anti-friction bearing especially adapted for use as a side bearing on railway cars, and wherein the same may be attached to the body bolster of the car, and the anti-friction element proper made self-centering, under the action of gravity.

10 A more specific object of the invention is to provide a side bearing of the swinging pendulum type, wherein the anti-friction element is swingingly suspended by a pivot pin at a point above the center of mass of said element, 15 and the actuating pressure is received directly by the pivot pin and transmitted from the latter to the anti-friction element through an interposed anti-friction roller.

In the drawing forming a part of this specification, Figure 1 is a vertical sectional view taken through the ends of a body and a truck bolster of a railway car, showing my improved anti-friction bearing in connection therewith. Fig. 2 is an end elevation looking from the left in Fig. 1, portions of the body and truck bolsters being shown in section. Fig. 3 is a section taken substantially on the line 3—3 of Fig. 1. And Fig. 4 is a perspective view of a guide member used in connection with my improved side bearing.

In said drawing, 10 denotes the upper portion of a truck bolster of a railway car, and 11 the opposed lower part or section of a body bolster. My improved side bearing is shown 35 attached to the body bolster. The improved bearing comprises, broadly, a retaining or supporting member A, an anti-friction element B, a pivot pin C, an anti-friction roller D, and a roller guide E.

40 The retaining or supporting member A is in the form of a hollow box-like casting, comprising vertically extending side walls 12—12 and end walls 13—13. The casting A is closed at its lower side by a horizontally extending wall 14 provided with a raised portion 15 at its center to provide a downwardly facing recess 16 adapted to receive the upper end portion of the anti-friction element B. The raised portion 15 is provided with an 45 upper flat face 17 adapted to bear on the under side of the body bolster 11. To attach the retaining member A to the body bolster 11, the end walls 13—13 are provided with laterally projecting lugs 18—18 secured to the 50 bolster 11 by rivets 19 or any similar attach- 55

ing devices. The side walls 12—12 of the retaining member A are provided with centrally located downwardly extending ears 20—20 of segmental form.

The anti-friction element B is of sector-like 60 form in outline, being provided with a lower curved bearing face 21 and upwardly extending, converging end faces 22—22 adapted to co-operate with the flat face of the bottom wall 14 of the retaining member A to limit 65 the swinging movement of the anti-friction element B. The anti-friction element B is also provided with upwardly extending spaced ears 23—23 located at opposite ends of 70 said element. The ears 23—23 are provided with alined irregular recesses 24—24. Between the ears 23—23, the anti-friction element B is provided with a curved bearing surface 25 concentric with the bearing surface 21 75 and adapted to co-act with the anti-friction roller D. The lower walls of the recesses 24—24 are in alinement with the curved face 25, forming a continuation thereof. The interior walls, at the upper ends of the recesses 24—24, are curved to correspond with the curvature of the cylindrical face of the pivot pin C forming bearing surfaces 26—26 adapted to co-act with the upper side of the pivot pin 80 C. The anti-friction element B is swingingly suspended and supported by the pivot pin C 85 fixed within recesses 27—27 in the ears 20—20 of the opposed side walls 12—12 of the retaining member A by pins 28—28 passing through suitably alined recesses in the pin C and in the ears 20 of the retaining member. 90

To prevent the pivot pin C from being distorted or bent under the operating pressure of the device, the retaining member A is provided with a post 29 downwardly projecting from the raised portion 15 and centrally located between the side walls 20—20. The post 29 is provided with a concave lower surface 95 corresponding in curvature to the cylindrical surface of the pivot C and forming an abutment for the same.

The anti-friction roller D is interposed between the lower side of the pivot pin C and the curved bearing surface 25, normally resting on said bearing surface and having its upper side spaced a short distance from the lower side of the pivot pin C. The roller D is retained in operative assembled relation with the other parts, by the downwardly extending ears 20—20.

The guide member E is of U-shape, being 110

provided with spaced depending side members 31—31 connected by upper curved strap portions 32—32. The latter are spaced apart to provide a recess 33 to accommodate the 5 post 29. The members 31—31 are arranged in parallel relation and spaced apart a distance approximately equal to the diameter of the anti-friction roller D to loosely receive the 10 same for sliding movement. The curved portions 32—32 of the member E are provided with lower curved bearing faces 34—34 corresponding in curvature to the curvature of the cylindrical face of the pivot pin C, and the member E is adapted to be swingingly 15 supported thereby on the pivot pin C.

When the parts are in assembled relation, the guide member E is disposed between the ears 23—23 of the anti-friction element B and the post 29 received within the recess 33 20 and the anti-friction roller disposed between the members 31—31. In this connection, it is pointed out that the guide member E is mounted for swinging movement independent 25 of the anti-friction element B, sufficient clearance being provided between the lower ends of the members 31—31 and the bearing face 25 to permit this movement.

As clearly shown in Fig. 1, proper clearance is provided between the lower curved 30 face of the raised portion 15 and the upper curved face 35 of the anti-friction element B to permit the pivot pin C and the roller D to be brought into contact without the upper face 35 of the element B actually engaging 35 the lower curved face of the raised portion 15 of the wall 14. In this connection, it will be noted that the curved faces 21 and 25 are so arranged that they will be concentric with the curved cylindrical face of the pivot pin 40 C when the roller D is moved into actual contact with the lower side of said pivot pin.

As the actuating pressure is received directly by the pivot pin C from the body bolster 11 and transmitted to the anti-friction 45 element B by the interposed roller D, it is desirable that the roller and pin be constructed of special material to resist wear. The pivot pin C and the roller D are both, preferably, made of alloy steel, and both heat-treated.

The pivot pin C is located above the center 50 of mass of the anti-friction element B, whereby the latter is caused to swing to its normal central position under the influence of gravity when the actuating pressure is removed from the bearing.

In the operation of my improved device, as the two bolsters 10 and 11 approach each other and shift radially, the element B will be elevated until the roller D engages against the lower side of the pivot pin C, the roller being guided in its upward movement by the 60 guide member E. It will thus be seen that the pressure from the body bolster is received directly by the pivot pin C and transmitted 65 through the roller D to the anti-friction ele-

ment B, rolling on the truck bolster 10. As the relative radial movement of the bolsters continues, the element B will be rolled as, for example, to the dotted line position shown in Fig. 1. This movement is limited by the 70 engagement of the side face 22 of the roller with the flat face of the wall 14 of the retaining member A. Upon separation of the bolsters or removal of the pressure upon the anti-friction element B, the latter will drop downwardly until it is directly supported by the pivot pin C. It will be seen that the anti-friction element B is thus swingingly suspended from the pivot pin C and adapted under the influence of gravity to swing to normal central position. The guide member E, being free to swing under the force of gravity, will return to normal position when the pressure has been removed or the truck is returned to its normal position.

The principal function of the guide member E is to hold the roller D in parallel relation with the pin C, thereby preventing the roller from getting out of alignment with the pin, when, parts are free to move.

While the load is transferred from the body bolster through the pin C, as heretofore explained, it will be noted from an inspection of Figure 3 that said pin C is not subject to any appreciable bending moment, since it is 95 supported at its ends and at the center, and the load is transferred from the pin C to the roller D which has contact with the pin C throughout the length of the latter, between its end supports.

I have herein shown and described what I now consider the preferred manner of carrying out the invention, but the same is merely 100 illustrative, and I contemplate all changes and modifications that come within the scope 105 of the claims appended hereto.

I claim:

1. In a device of the character described, constructed to be suspended from the under side of a body bolster; the combination with 110 an anti-friction element having a lower convex bearing face and an upper concave bearing face; of means for pivotally supporting said element above the center of mass thereof; an anti-friction roller interposed between 115 said means and the concave face of said bearing; and a guide member for said roller, said guide member being pivotally supported for movement independent of said element.

2. In an anti-friction bearing of the character described, constructed to be secured in a depending position on the under side of a bolster or the like, the combination with a supporting member having a part with a convex bearing face; of an anti-friction element 125 hung from said member for swinging movement, said element having convex and concave concentric bearing surfaces; an anti-friction roller interposed between said concave surface of said element and the convex face of 130

said member; and a guide member for said roller suspended from said member for swinging movement relative to said element.

3. In an anti-friction bearing of the character described, constructed to be secured in a depending position on the under side of a bolster or the like, the combination with a retaining member; of a pivot pin anchored in said member; a swinging anti-friction element loosely hung on said pivot pin to permit limited upward movement of said element relatively to said pin, said element being provided with a lower convex bearing surface and an upper concave bearing surface; a roller interposed between said pivot pin and said concave bearing surface, said roller normally being spaced a limited distance from said pin and resting on said concave surface, said roller also being adapted to engage with said pivot pin, upon actuating pressure being applied, and transmit the load from said pin to said element; and a guide for said roller, said guide being movable independently of said element and adapted to return the roller to normal position under the influence of gravity.

4. In an anti-friction bearing of the character described, constructed to be secured in a depending position on the under side of a bolster or the like, the combination with an anti-friction element having a lower convex bearing surface, the upper end portion of said element being recessed, and the opposed upper and lower portions of the wall of said recess being curved to provide bearing surfaces; of a retaining member; a pivot pin fixedly mounted in said support and co-acting with the upper curved bearing surface of said recess to swingingly support said

element with the point of support above the center of mass thereof; a roller interposed between said pivot pin and the lower curved bearing face of said recess, said roller normally being supported on said last named bearing face and spaced a limited distance from the lower curved bearing face of said pivot pin; a swinging roller guide comprising a pair of depending spaced arms connected by an upper curved bearing portion, said curved bearing portion of said guide co-acting with the pivot pin to swingingly support said guide, and said spaced arms loosely embracing said roller to guide the latter.

5. In an anti-friction bearing of the character described, the combination with a retainer adapted to be secured to a body bolster, said retainer being provided with spaced depending walls; of an elongated cylindrical pivot pin having its ends mounted in said walls and extending continuously therebetween; a rocker having a convex bearing surface adapted to engage a truck bolster, said rocker being provided with an upper concave bearing surface, said rocker having ears provided with recesses for the reception of said pivot pin, to support said rocker for swinging movement, said recesses being elongated and transversely widened at their lower ends; and a roller interposed between said pivot pin and the concave surface of said rocker, said roller having its ends disposed in the transversely widened portions at the lower ends of said recesses.

In witness that I claim the foregoing I have hereunto subscribed my name this 18th day of November, 1922.

JOHN F. O'CONNOR.
